(74) **Attorney, Agent, or Firm:** Rumit Ranjit Kanakia

(57) **CLAIM**

I claim the ornamental design for an earphone, as shown and described.

DESCRIPTION

FIG. 1 is a Perspective view of an earphone showing my new design;

FIG. 2 is a Right-side view thereof;

FIG. 3 is a Left-side view thereof;

FIG. 4 is a Front view thereof;

FIG. 5 is a Back view thereof;

FIG. 6 is a Bottom view thereof; and,

FIG. 7 is a Top view thereof.

The broken lines depict portions of the earphone that form no part of the claimed design.

1 Claim, 7 Drawing Sheets
